GAME APPARATUS

Harvey R. Hawgood, Cleveland, Ohio

Application November 12, 1934, Serial No. 752,580

9 Claims. (Cl. 35—8)

This invention relates to games and to apparatus for use in playing the same.

An object of the invention is to provide an improved series of articles or apparatus for playing games which will enable the participant to determine his course of action.

Another object is to provide an improved series of articles for playing a game which will convey to the mind of a player the characteristics or values of various combinations of said articles.

Another object is to provide an improved series of articles for playing a game which will facilitate the teaching of games to beginners.

Another object is to provide an improved series of articles which will reduce the mental calculations which must be made by the player.

Other objects will hereinafter appear.

The invention will be better understood from the description of two practical embodiments thereof, illustrated in the accompanying drawing, in which:

Figure 1 is a view of a series of cards embodying the invention arranged to show one side and one end of each card;

Figure 2 is a view of a different series of cards similar to those of Figure 1 and arranged to illustrate one way in which they may be used.

Figure 3 is a view of the cards shown in Figure 2, but showing them arranged to illustrate another manner in which they may be used; and

Figure 4 is a view of a series of cards differing from those of the first three figures and arranged to be used in the same manner as the cards shown in Figure 2.

The cards illustrated are intended for use in playing the game known as "contract bridge", but it will be apparent that the invention may be applied to many other games.

With the cards illustrated, it would be possible more easily to play "auction bridge" and only slightly different mathematical calculations and re-arrangement would be required to adapt the deck to such games as "five hundred" and the like, where the type of play depends upon the taking of tricks.

It will be understood that the cards illustrated are merely typical and that for playing bridge a full deck of fifty two cards of conventional denominations running from the deuce to the ace in the four common suits would be used, while in some of the other games the elevens and twelves in the four suits, jokers, and other cards might be added.

The cards themselves will be referred to hereinafter by their own commonly accepted names as "ace", "king", "queen", etc., rather than by additional reference numerals applied thereto.

Incidentally, the series of cards shown embodies, in those markings which are intended to show the trump value of the hand, one well

known system of bridge game to indicate the method of bidding; in those indicating the no-trump value, another well known system. It will be obvious that either series of markings may be based upon any desired system of calculation and that the two chosen here, like the game, are selected merely for illustrative purposes.

Six cards appear in Figure 1, and it will be understood that markings such as shown upon the ace, king, queen, jack and ten of spades will be provided on the corresponding cards of each of the other suits. The remaining cards of the deck, namely from the deuce to the nine in all four suits, are provided with markings identical to those shown on the four of spades.

It will be obvious that the usual spots, faces and pips may be provided upon the cards so that they resemble very closely those of a conventional deck. For convenience, the size of the conventional markings may be reduced, particularly that of the pips, which will permit the lines to be moved nearer the tops of the cards. Thus a beginner plays with cards carrying all the symbols found in the conventional deck and learns automatically to evaluate a hand without having to stop and make mental calculation of the combinations of card which occur in it.

It will be noted that there are two series of markings or indicia, one along the sides of the cards and one along the tops thereof, the former being for use in determining the trump value of a hand, and the latter for determining the no-trump value thereof. According to the system used by some players, no-trump values may be based upon the same indicia used for trump values. The markings consist of series of lines so arranged that when the cards are arranged in the manner in which they are normally held in the player's hand, that is, with those of the same suit grouped together with the highest card of the suit to the left, the cards of the suit arranged in numerical order or importance, from the highest card to the lowest at the right, these lines will indicate a path from card to card. This path is provided with indicia which indicate directly to the mind of the user the value of the various combinations of cards.

As is well known in the playing of contract bridge, the value of the cards in any particular suit depends mainly upon combinations including one or more of the five highest or "honor" cards, and are assigned certain values known as "honor tricks".

For instance, the ace alone is worth one honor trick, the ace and king two honor tricks, the ace and queen one and one-half honor tricks, the king and queen one honor trick, the king-queen and jack or ten one-half honor trick, and so on. Also, that unless a hand contains a certain number of honor tricks, it is not sufficiently strong.

to warrant a trump bid. Further, that a trump should not be bid in any suit which does not contain sufficient strength and length.

For instance, an original bid by the first bidder requires that he hold at least $2\frac{1}{2}$ honor tricks in his hand and to bid a suit for trump, he must have at least four cards of the suit bid and $1\frac{1}{2}$ honor tricks in this suit. In other positions, and after other bids, different values are required.

10. The markings and indicia accompanying them illustrated in the drawing make it possible for the bidder, after arranging his cards, at a glance to determine the value of honor tricks in each suit, and whether or not the suit is biddable, in the following manner:

15. Upon the ace is placed an arrow 11 marked as shown with the numeral "1" and the word "Start". The numeral indicates the honor trick value of this card alone, and the arrow and word "Start" indicate that the player holding this card should trace a path along a line starting from this arrow.

20. On the king is a line 12 arranged at the same position along the side of the card as arrow 11, and associated with this line is a numeral "2" so that when the ace and king are placed side by side the path from the arrow 11 runs along the line 12, and the honor trick value of the combination is indicated by the numeral "2".

25. In other words, the one trick value of any combination is indicated by the highest numeral appearing along the path starting from the arrow on the highest card of the suit.

30. The king also bears an arrow 13 which is marked "Start if high", which is to indicate that if the player holds the king but not the ace, his path will start from this point.

35. Similarly on the queen is a line 14 arranged at a position along its edge to be brought into alignment with the inner end of line 12 when the king and queen are placed together. It is also provided with a line 15; the outer edge of which is arranged to come into alignment with arrow 11 when the ace and queen are placed together and bears numeral "1 $\frac{1}{2}$ " indicating the value of the ace-queen combination. It likewise has a line 16 arranged to be aligned with the arrow 13 of the king and bearing a numeral "1" to indicate the one honor trick value of the king-queen trick combination.

40. Below these lines is an arrow 17 marked, as in the case of the arrow on the king, with the legend "Start if high" and indicates the starting point of the path in the case of a queen-high combination.

45. Upon the jack similar lines are placed, line 18 being arranged to serve as a continuation of line 14 on the queen, line 19 as a continuation of line 12 on the king or of line 15 on the queen. Line 20 is a continuation of line 16 on the king; 21 is a continuation of arrow 11 on the ace; line 22 of the arrow 13 on the king; line 23 of the arrow 17 on the queen, and the arrow 24 marked "Start if high" for the beginning of the path in jack high combinations.

50. It will be noted that line 18 bears an index 25, shown as the letter "B", which is the symbol of a biddable suit. In other words, if the path starting from the arrow on the highest card reaches any line provided with this symbol, the player knows instantly that the suit in his hand has both sufficient length and strength to warrant him in bidding it.

55. The ten likewise has a series of lines which will come into alignment with the ends of any

of the previously mentioned lines or arrows, and which bear inscriptions indicating honor trick value of combinations including this card. The first line 26 is precisely like line 18 on the jack, and like it indicates a biddable suit. Line 27 5 bears a different index 28, shown as an asterisk, which indicates that the path from the highest arrow reaches this point that the suit is biddable in certain exceptional, but not all, circumstances.

60. For instance, it indicates the biddability of a four-card suit in a hand holding five honor tricks, which, under the system being discussed, warrants a bid of two as an original bid. Line 28 which is arranged to serve as a continuation of arrow 17 on the queen indicates an honor card 15 value of $\frac{1}{4}$, but, as this combination is worth $\frac{1}{2}$ if the king and a "spot" of some other suit appear in the hand, this is indicated by the legend appearing in the parentheses $(+KX=\frac{1}{2})$. Similarly, line 29 indicates a combination which 20 is worth $\frac{1}{4}$ only if the queen and a "spot" appear in some other suit, which is indicated by the legend $(+QX=\frac{1}{4})$.

65. The marks on the "spots" below the ten are similar to those of the latter, with a slightly 25 differing arrangement of the groups coming to points 30 and 31.

70. In Figure 2, a typical combination of cards in the heart suit is illustrated. These have been arranged as above described, reading from high 30 to low. The player, after arranging the cards in this order, aligns their edges as by resting them upon the table, and, starting with the arrow 13, runs his eye along the path it traces, which shows him instantly numeral "1" appearing on 35 the ten spot, and that the end of the path arrives at the symbol "B" on the four spot, so that without any mental calculation he knows the honor card value of this suit to be one and the 40 suit to be biddable.

75. He follows the same procedure with the three other suits, and, if he finds $1\frac{1}{2}$ more tricks amongst these, knows that he can make a one-heart bid upon the hand.

80. In Figure 4 a series of cards is shown having 45 marks similar to those of the first two figures but arranged so that the cards may be aligned while held in the hand spread in fan-wise fashion.

85. For the purpose of properly aligning the cards, each of them has been provided near its top with 50 a base line 100 and the player merely arranges his cards with these base lines forming a continuous line across the cards of one suit. This brings the various lines on the sides of the cards in proper relation to each other, so that they 55 may be read as in the embodiment above described.

90. With the group of cards illustrated, the path of eye starts with the arrow 111 and travels along 60 its route to the symbol 125 from which it is apparent the cards illustrated constitute a biddable suit and that the honor trick value of this suit as shown by the numeral on line 115 is "1 $\frac{1}{2}$ ".

95. While it is possible from the honor trick value of the various suits to determine the value of the hand at no-trump, another method of determining this has been provided. This is based upon another system of bidding, in which, for determining the no-trump value of the hand, the various cards from the ten to the ace are given 70 different values, the value of the ten, for instance, being $\frac{1}{2}$, and the ace 4.

100. These values are added together, and twelve or more points are necessary to warrant a one no-trump bid, depending upon the position of 75

the hand and the preceding bids. This is commonly known as the "point count", and means for indicating it are shown in Figures 1 and 3 arranged along the tops of the cards. Upon the 5 top of the ace is placed an arrow 41 bearing the legend "Start" and the numeral "4". This is to indicate the beginning of the path which the user's eye should trace, just as the arrow 41 does with regard to the marks on the sides of the 10 cards.

Upon the king is a line 42 the upper end of which is at the same position laterally as the arrow 41, this line being accompanied by the numeral "7" which indicates the combined value 15 of the ace and king.

This card also carries an arrow 43 with the inscription "Start if high" and the numeral "3".

Similar lines and arrows appear upon the queen, jack and ten, the lines on each card being so 20 arranged that they will serve as a continuation of any line or arrow on any of the preceding cards, and each having accompanying it the point-count value of the combination which it represents.

25 In the use of these insignia, the cards are arranged as shown in Figure 3, the path traced from the highest arrow along the line showing that the total value of the cards illustrated is 4½. Consequently, with the heart cards shown, 30 it would be necessary to have 7½ in a "point count" in the other three suits in order to bid one no-trump.

In Figure 4 an aligning line 140 is provided adjacent the upper right hand corner of the card 35 and beneath this on each of the cards are arranged arrows and lines 142 corresponding to those illustrated at the tops of the cards in Figure 1. The arrangement is such that when the cards are fanned out to expose their upper right-hand corners, as by shifting the lower cards to the right, or inverting the cards as shown in this figure, these lines may be read across the cards in the same manner as the lines along the tops are read on the cards of Figure 3. The cards are, 40 of course, aligned before reading them in the same manner as was described in conjunction with the lines on the left hand edges thereof.

It will be understood that reference to "playing" a hand herein includes the bidding of the hand and/or otherwise playing the hand, as by 45 "melding" or the actual laying down of the cards upon tricks or the like.

While I have described the illustrated embodiments of my invention in some particularity, obviously many others will readily occur to those skilled in this art, and I therefore do not limit myself to the precise details shown and described, but claim as my invention all embodiments, modifications and variations coming within 60 in the scope of the appended claims.

I claim:

1. A deck of playing cards some of which are provided with indicia indicating a starting point and others of which are provided with indicia serving as continuations of said first mentioned indicia and indicating a playing informational characteristic of the group of cards.

2. A deck of playing cards, some of which are provided with indicia indicating a characteristic of these cards when taken alone, and others of which are provided with indicia serving as con-

tinuations of said first mentioned indicia and indicating characteristics of a plurality of cards, and others of which are provided with indicia acting as continuations of said second mentioned indicia and indicating playing characteristics of 5 a group of cards.

3. A deck of playing cards, lines thereon, the lines on the cards having extreme values indicating selectively lines on successive cards, and the lines on successive cards arranged to continue the lines on the first mentioned cards across intermediate cards to the most remote card of a group, and indicia associated with said lines giving a playing informational characteristic of any group of cards. 10

4. A suit of playing cards comprising a series of cards marked to indicate a definite sequence of value, lines on some of said cards adjacent a vertical edge and indicating a starting point, lines on other of the cards adjacent a corresponding 20 vertical edge and adapted to be brought into alignment with said first mentioned lines and serving as a continuation thereof, said lines extending on the face of the card and in general in the direction of said edge and terminating in 25 ends adapted to be brought into alignment with lines on other of the cards, the lines being provided with indicia indicating a playing characteristic of groups of the cards.

5. A slide-rule-like calculating device comprising a plurality of interchangeable slides, each having alining means, the aligning means being similarly positioned on each of said slides whereby any two or more may be properly aligned 30 with each other, and provided with indicia indicating functions of any combination of said slides.

6. A slide-rule-like calculating device comprising a plurality of interchangeable slides, each slide having alining means, the slides being relatively thin, whereby they may be conveniently arranged in overlapping relation, and each provided with indicia adjacent one edge visible when the slides are arranged in overlapped relation and indicating functions of any combination of 45 said slides.

7. A slide-rule-like calculating device comprising a series of slides, each corresponding to a playing card and provided with the indicia found on such playing card, the slides each having 50 alining means and indicia indicating playing informational characteristics, said indicia arranged when any number of slides are placed in alinement to indicate a playing informational characteristic of that particular group of cards 55 represented by the slides.

8. A slide-rule-like calculating device comprising a plurality of normally separated slides of thin sheet material, each having indicia along one edge, whereby the slides may be overlapped 60 in any desired combination, and the indicia of the entire combination visible to indicate a function of two or more slides.

9. A slide-rule-like calculating device comprising a plurality of normally separated slides of thin sheet material, each having alining means and indicia along one edge, whereby the slides may be overlapped in any desired combination, and the indicia of the entire combination visible to indicate a function of two or more slides. 70

HARVEY R. HAWGOOD.
